(57) **CLAIM**

The ornamental design for a cable tie installation tool, as shown and described.

DESCRIPTION

FIG. 1 is a top left front perspective view of a cable tie installation tool in accordance with the invention;

FIG. 2 is a top right front perspective view of the cable tie installation tool of FIG. 1;

FIG. 3 is a bottom left rear perspective view of the cable tie installation tool of FIG. 1;

FIG. 4 is a left side elevational view of the cable tie installation tool of FIG. 1;

FIG. 5 is a right side elevational view of the cable tie installation tool of FIG. 1;

FIG. 6 is a top plan view of the cable tie installation tool of FIG. 1;

FIG. 7 is a bottom plan view of the cable tie installation tool of FIG. 1;

FIG. 8 is a front elevational view of the cable tie installation tool of FIG. 1; and,

FIG. 9 is a rear elevational view of the cable tie installation tool of FIG. 1.

The broken line showing of environmental structure is for illustrative purposes only and forms no part of the claimed design.
